HEWITT A. GEHRES, OF MOUNT VERNON, OHIO.

ENGINE-CYLINDER-SCAVENGING MECHANISM.

Application filed March 17, 1924. Serial No. 699,693.

The invention relates to a scavenging mechanism for internal combustion engines, more especially of the two-cycle type. One feature of the invention relates to the provision of a port at one end of the cylinder for directing a stream of scavenging air longitudinally therethrough. The valve for controlling a port of the above nature usually must be of large size in order to afford an adequate area of opening, and it is desirable to employ a valve which will open quickly in order to provide unimpeded flow of the scavenging air at all times when the valve is open. However, it is difficult to provide a valve which will satisfy both of the above requirements, since if a large valve is accelerated when opening and closing, excessive noise is created due to slamming against the valve seat, and, on the other hand, if the valve opens and closes slowly, its area of opening at these times is unduly small.

One object of the present invention is to provide a scavenging valve which will have an adequate area of opening at all times, and avoid mechanical difficulties such as are above mentioned.

Another object of the invention is to improve the scavenging action by combining with a valve of the above character, a scavenging port located adjacent the opposite end of the cylinder and near the exhaust port thereof, in such manner as to secure the combined effect of a stream of scavenging air traveling longitudinally through the cylinder and a local transverse stream of air near the exhaust port, to the end that all parts of the cylinder may be thoroughly scavenged.

Other objects and advantages of the invention will be in part obvious and in part specifically pointed out in the description hereinafter contained, which, taken in connection with the accompanying drawings, discloses certain preferred embodiments thereof; such embodiments, however, are to be considered merely as illustrative of its principles. In the drawings:

Fig. 1 is a central longitudinal section of an engine cylinder equipped with a scavenging mechanism operating in accordance with the invention.

Figs. 2 to 5 are views similar to Fig. 1, showing the scavenging mechanism in different positions which it assumes during the cycle of the engine.

Fig. 6 is a view similar to Fig. 1, but showing a modified form of the invention.

Fig. 7 is a graphic chart showing the valve and port openings of the scavenging mechanism as shown in Figs. 1 to 6.

In Fig. 1 I have shown an internal combustion two-cycle engine cylinder 1 which may be, for example, of the Diesel type, and having a piston 2 which uncovers an exhaust port 3 toward the end of its power stroke. Certain component parts of the engine will not be described herein, since the present invention is not particularly concerned with them.

In accordance with the present invention I provide in or adjacent the cylinder head 4, a scavenging port 5 through which the air to be employed for scavenging purposes is led in any suitable manner, as by a passageway 6 in the cylinder head. A valve 7 controls communication between the port 5 and the cylinder head, the illustrated valve being of the poppet type, and having a valve stem 8 actuated to open and close valve 7 at the proper times. In the present instance the valve is actuated by a rocker arm 9 pivoted to a bracket 10 extending from the cylinder head 4, the arm 9 being moved back and forth in timed relation to the motion of the piston, to open and close valve 7 at the proper times. To avoid undue noise in the operation of valve 7 it is preferably moved slowly in opening and closing, but may be moved relatively quickly in intermediate positions. This motion may be imparted by any suitable valve gear; in Fig. 2, for example, I have shown conventionally crank 9^a, which is connected to the arm 9 by a link 9^b, to typify the motion of the valve.

An auxiliary valve 11 is interposed between the port 5 and the passageway 6, in such manner that the scavenging air does not necessarily flow into the cylinder at all times when valve 7 is open, and the auxiliary valve 11 is arranged to open somewhat later than valve 7. In the form of the invention illustrated in Fig. 1, the auxiliary valve 11 is of the piston type and slides within a sleeve 12 interposed between port 5 and passageway 6, but provided with openings 13 which are uncovered in certain positions of valve 11. The valve 11 is shown as fixedly carried by stem 8 of valve 7, and as valve 7 moves to full open position, the

valve 11 will move downward sufficiently to uncover the openings 13 in sleeve 12, and holes 14 in the valve will uncover the lower openings 13 in such sleeve.

Accordingly, in the operation of the engine, the valve 7 may be partially opened, prior to the time when it is desired to have scavenging air enter the cylinder; and valve 11 will be opened at just the time the scavenging air is desired. When the auxiliary valve 11 opens, valve 7 will already have moved away from port 5 sufficiently to afford a large opening in such port through which the scavenging air may pass; and as above stated the motion of valve 7 may be accelerated as it moves away from port 5, to the end that valve 11 will open rapidly and at once admit a full volume of air to the cylinder. Similarly, when the valve closes, the auxiliary valve 11 will first travel over the openings 13 at a relatively rapid rate and cut off communication between the port 5 and passageway 6. Valve 7 will then be moved slowly to full seated position against the walls of the port 5.

If it were attempted to open and close the valve 7 quickly enough to admit and shut off the air as suddenly as desired, the operation of the valve would create excessive noise, but with an auxiliary valve as above described the valve 7 may be opened and closed so slowly as to permit smooth quiet operation, and yet admission and cut-off of the scavenging air will be brought about quickly and without undue restriction in the areas of valve opening afforded. Unless an auxiliary valve be employed as above described, an opening motion of the valve 7 slow enough to avoid excessive noise, and other mechanical difficulties, will unduly restrict the area of the valve opening afforded in the initial stages of moving the valve to or from its valve seat.

Preferably the cylinder is also provided with a scavenging port 15 located in the region of exhaust port 3, and directing a stream of air transversely across the head of piston 2 to the exhaust port. Thus the cylinder is scavenged by the combined action of the stream of air passing longitudinally through the cylinder from port 5, and a further stream of air which enters through port 15 and sweeps directly across over the head of the piston and into the exhaust port. The longitudinal stream of air above mentioned modifies the transverse stream in such a way as to guide the latter into a transverse path of movement across the portion of the cylinder in which the longitudinal stream is least effective. The transverse stream of air accordingly does not pass upwardly to the top of the cylinder and then have to reverse itself in passing to the exhaust port 3, as otherwise would be the case.

Although the scavenging port 15 is preferably employed, it will be understood that it may be dispensed with, and the longitudinal stream of air issuing through port 5 alone depended on for scavenging.

In the position of parts as shown in Fig. 1, the piston 2 is approaching the end of its power stroke, and has just uncovered exhaust port 3. Valve 7 has moved to partially open position, but no scavenging air has yet entered the cylinder since auxiliary valve 11 is still closed, and the piston has not yet uncovered port 15.

As shown in Fig. 2, the piston has moved downwardly to dead centre upon completion of its power stroke; valve 7 has moved to full open position and valve 11 has also opened, thus admitting the longitudinal stream of air above described. The piston has also uncovered port 15, thus admitting the transverse stream of scavenging air.

In Fig. 3 the piston has moved upwardly a sufficient distance to cover port 15, but valve 7 and also auxiliary valve 11 are still open, permitting the longitudinal stream of scavenging air to still pass through the cylinder and out through exhaust port 3.

According to Fig. 4 the piston has moved up still further to close exhaust port 3, but air is still permitted to enter the cylinder, since valve 7 is still open, and the auxiliary valve 11 is only just beginning to close. The scavenging mechanism thus permits supercharging of the cylinder to take place.

Fig. 5 shows the piston 2 still further advanced upon its compression stroke, the valve 7 being still partially open, but valve 11 being closed, whereby the supply of scavenging air is cut off.

Fig. 7 shows diagrammatically the condition of the various port openings at various times in the cycle of the engine when the valves or ports are open, the valve and port openings being plotted against time. Point 16 at the left of the figure shows zero openings for all the ports, and exhaust port 3 and valve 7 are just beginning to open. The area of the exhaust port is indicated in the diagram by the abscissal of the larger triangle having the criss cross lines at its sides. The amount of opening of valve 7 is shown by the points on line 17. At the point 18 valve 11 opens and also piston 2 begins to uncover port 15, and the area of opening of port 15 is indicated by the vertical lines in the smaller central triangle of Fig. 7 between the point 18 and the point 19, at which latter point the port 15 is again closed. The combined scavenging port area is denoted by the total length of the vertical sectional lines in Fig. 7, and exhaust continues until the point 20 is reached, when the exhaust port 3 closes. The valve 11, however, remains open a further period until the point 21 is reached, and

thus the vertically sectioned area between point 20 and 21 indicates the amount of supercharging or building up of pressure in the cylinder, which continues until the 5 auxiliary valve 11 closes. Valve 7 then closes slowly at the point 22.

Fig. 6 also illustrates diagrammatically a modified form of the invention wherein the auxiliary valve 11^a, instead of being mechanically timed to open later than the valve 7, is operated automatically by changes of the cylinder pressure. This valve may be, for example, what is known in the art as a plate valve, which will open automatically 10 after valve 7 has been opened and the exhaust port 3 has proceeded sufficiently to reduce the pressure in the cylinder to a value below that at which the scavenging air in chamber 23 is supplied. The valve 11^a will 15 then remain open until piston 2 has proceeded far enough in its compression stroke to build up a supercharging pressure in the cylinder, greater than that in scavenging air chamber 23.

25 While certain embodiments of the invention have been described, it will be obvious that many changes may be made therein without departing from its principles, as defined in the following claims.

30 I claim:

1. A cylinder scavenging mechanism comprising a scavenging port at the head of the cylinder, a valve therefor, and an auxiliary valve controlling communication to said port, said auxiliary valve being timed to remain closed during the initial stage of opening of said first mentioned valve and then open to admit scavenging air through said port to the cylinder. 35 2. A cylinder scavenging mechanism comprising a scavenging port at the head of the cylinder, a valve therefor, and an auxiliary valve controlling communication to said port, said auxiliary valve being timed to remain closed during the initial stage of opening of said first mentioned valve and then open to admit scavenging air through said port to the cylinder, said auxiliary valve also closing earlier than said first mentioned 40 valve. 50

3. A cylinder scavenging mechanism comprising a scavenging port at the head of the cylinder, a valve adapted to seat against the walls of said port, actuating means for said 55 valve adapted to move the same relatively slowly when near the walls of the port, and more rapidly in intermediate positions, an auxiliary valve controlling communication to said port, said auxiliary valve being timed to remain closed during the initial stage of opening of said first mentioned valve, and then open to admit scavenging air through said port to the cylinder. 60

4. A cylinder scavenging mechanism comprising a scavenging port at the head of the 65

cylinder, a valve adapted to seat against the walls of said port, actuating means for said valve adapted to move the same relatively slowly when near the walls of the port, and more rapidly in intermediate positions, an auxiliary valve controlling communication to said port, said auxiliary valve being also moved by said actuating means and timed to open the auxiliary valve when the first mentioned valve is being moved relatively rapidly, to admit scavenging air through said port to the cylinder. 70 75

5. A cylinder scavenging mechanism comprising a scavenging port at the head of the cylinder, a poppet valve for said port, an auxiliary valve of the piston type controlling communication to said port, and connected to the stem of said poppet valve, said piston valve being timed to remain closed during the initial stage of opening of said poppet valve and then open to admit scavenging air through said poppet valve to the cylinder. 80 85

6. A cylinder scavenging mechanism comprising a scavenging port located near the head end of the cylinder and positioned to direct a stream of scavenging air longitudinally through the cylinder, a valve for said port, an auxiliary valve controlling communication to said port, said auxiliary valve being timed to remain closed during the initial stage of opening of said first mentioned valve and then to open to admit scavenging air through said port to the cylinder, an exhaust port located near the opposite end of the cylinder and a further scavenging port located in the region of the exhaust port and admitting a transverse stream of scavenging air across the cylinder to the exhaust port, when the latter is open. 90 95 100 105

7. A cylinder scavenging mechanism comprising a scavenging port located near the head end of the cylinder, a valve therefor, an auxiliary valve controlling communication to said valve whereby scavenging air may pass into the cylinder only when both of said ports are open, said auxiliary valve being timed to close prior to said first mentioned valve. 110

8. A cylinder scavenging mechanism comprising a scavenging port located near the head end of the cylinder, a valve therefor, an auxiliary valve controlling communication to said port whereby scavenging air may pass into the cylinder only when both of said valves are open, an exhaust port in said cylinder, said valves both being timed to remain open after the exhaust port has closed, and said auxiliary valve closing prior to said first mentioned valve. 115 120 125

In testimony that I claim the foregoing, I have hereunto set my hand this 15th day of February, 1924.

HEWITT A. GEHRES.
